UNITED STATES PATENT OFFICE.

LA FAYETTE LILLARD, OF DIXON, CALIFORNIA.

TRACTION-ENGINE.

SPECIFICATION forming part of Letters Patent No. 278,154, dated May 22, 1883.

Application filed October 7, 1882. (Model.)

To all whom it may concern:

Be it known that I, LA FAYETTE LILLARD, a citizen of the United States, residing at Dixon, in the county of Solano and State of California, have invented a new and useful Steam Traction-Engine, of which the following is a specification.

My invention relates to improvements in steam traction-engines in which each driving-wheel has two bearings, one of which is an axle attached to end of boiler, and the other bearing is on anti-friction rollers surrounding boiler; and the objects of my improvements are, first, to provide strength with as little weight as possible; second, to afford facilities for preventing flues from heating while out of water; third, to provide driving-wheels with surface sufficient to prevent them from sinking deep into the ground. I attain these objects by the mechanism illustrated in the accompanying drawings, in which—

Figure 1 is a vertical and longitudinal section of the boiler with one driving-wheel. Fig. 2 is a vertical cross-section of boiler and driving-wheel with its anti-friction rollers. Fig. 3 shows a perspective view of driving-wheel.

Similar letters refer to similar parts throughout the several views.

The boiler B forms a part of the frame-work of the engine.

F is the fire-box at the middle of boiler. The flame and heated air enter the flues g g, and return through the flues h h to the smoke-box S.

P is a partition which separates the smoke-box from the fire-box.

D is a safety-damper so adjusted that it can be made to close either of the return-flues h h. This is to be done when the water leaves the flues of the higher end of the boiler. This will prevent the flues from heating hot enough to cause a collapse.

W is the driving-wheel, with one bearing on the axle X, which is attached to the end of the boiler. The other bearing is on the anti-friction rollers r r. These rollers roll on the grooved ring c c, which surrounds the boiler and acts as a guide for the anti-friction rollers r r. These anti-friction rollers revolve on axles attached to the ring v v, which holds them in their relative positions. There is also within the wheels a groove, m, which, in conjunction with ring c c, guides the anti-friction rollers.

The plan of communicating motion to the driving-wheel is not shown in the drawings, as I do not claim any improvement over the old methods.

What I claim as my invention, and desire to secure by Letters Patent, is—

The combination, in a steam traction-engine, of an axle, X, attached to the end of boiler B, and a driving-wheel, W, which has two bearings—viz., one on the axle X, and the other bearing on the anti-friction rollers r r, which surround the boiler B—all substantially as set forth.

LA FAYETTE LILLARD.
